UNITED STATES PATENT OFFICE.

WALTER N. VANCE, OF CHICAGO HEIGHTS, ILLINOIS, ASSIGNOR TO DURAND STEEL LOCKER CO., OF CHICAGO, ILLINOIS, A CORPORATION OF ILLINOIS.

LOCKING DEVICE FOR LOCKER DOORS.

1,424,533.

Specification of Letters Patent. Patented Aug. 1, 1922.

Application filed October 25, 1917. Serial No. 198,407.

To all whom it may concern:

Be it known that I, WALTER N. VANCE, a citizen of the United States, residing in Chicago Heights, in the county of Cook and

5 State of Illinois, have invented a new and useful Improvement in Locking Devices for Locker Doors, of which the following is a specification.

This invention relates in general to locks and more particularly to locks for locking the doors of the same.

Prior to my invention it has been generally the custom to provide lockers with rim locks, i. e. having a rim which extends 10 about the lock body and is secured to the door and may be operated by either a key or a combination device upon the outside, the latch or bolt being usually located within the locker. Frequently, however, it is desirable in the manufacture of lockers to provide the locker with a locking arrangement 15 permitting the use of a padlock instead of the rim lock and this has required the special formation of the door,—that is to say, 20 the formation of the door differs from the formation of the door where the rim lock is used.

It is a principal object of this invention to provide a locker door and a padlock locking 25 device which may fit through the door in place of the rim lock and without requiring the construction of the door to be changed, so that standard doors may be constructed and later fitted with the padlock locking device and with the rim locks either with the 30 combination or key device as the purchasers may require.

A further object of the invention is the provision of a door locking mechanism 35 adapted to be secured by a padlock, which will require that the padlock pass only through a single apertured member instead of engaging through two members as is frequently the custom, which locking device 40 will also be constructed of a single moving part not likely to become damaged or disarranged in use.

A still further object of the invention is the provision of a latch adapted to be secured by a padlock, which will be of obvious 45 and easy operation and which will not detract from the appearance of the locker equipped therewith.

Other objects and advantages of the invention will be apparent as it is better un-

derstood from the following description when considered in connection with the accompanying drawing illustrating a preferred embodiment thereof.

On the drawing,

60 Figure 1 is a partial front elevation of a locker in which my present invention is embodied;

Fig. 2 is a partial, enlarged rear view of the locking device adapted for engaging 65 with the padlock and showing the same in locked position;

Fig. 3 is a similar view showing the same in unlocked position;

Fig. 4 is a section taken substantially on 70 the line 4—4 of Fig. 2;

Fig. 5 is a section taken substantially on the line 5—5 of Fig. 3;

Fig. 6 is an enlarged partial front elevation showing the arrangement with the rim 75 lock in place;

Fig. 7 is a similar view taken from the rear;

Fig. 8 is a fragmentary view showing the construction of the door to permit either 80 lock, i. e., the padlock or the rim lock to be secured in place;

Fig. 9 is a top plan view of the latch or bolt of the padlock engaging lock;

Fig. 10 is a side view of the same; and

Fig. 11 is a side elevation of the plate 85 carrying this latch.

For the purpose of illustrating my invention I have shown on the drawing a locker 15 of any usual or preferred construction, having a frame 16 and a door 17 hinged at 18 in said frame. The door in the present instance is provided with a latch bar 19 adapted to be lifted vertically by a handle 21 extending through the door. The bar 19 is held in place by keepers 22 extending through slots 23 in the bar and fastened in the frame. The door is provided with an inwardly extending flange or edge 24 which enters into U-straps 25 secured at 26 in the 100 frame and extending into the door opening. Opposite the straps the bar 19 is offset and provided with downwardly extending tongues 27 adapted to engage in slots or notches 28 in the straps 25 to hold the door 105 in latched position.

Viewing Fig. 8 it will be noted that the door is provided with an aperture 29 and a pair of relatively small apertures 31, the aperture 29 being adapted to permit a lock- 110

ing device to extend out through the door and the apertures 31 being provided to receive holding bolts or other devices. A facing plate 32 provided with apertures 5 aligning with apertures 29 and 31 is secured on the front of the locker by bolts 33 extending through the apertures 31.

In accordance with my invention it is intended that either a rim lock or a padlocking device be secured by the bolts 33 to extend through the aperture 29 for manipulation by the user. The padlocking device is shown in detail in Figs. 2 to 5 and 9 to 11 and the rim lock is shown diagrammatically 15 in Figs. 6 and 7, the inner construction of the rim lock being unimportant and being of the key or combination type.

Considering first the rim locking device, it will be noted that it consists of a latch 20 housing 34 having a pair of wings 35 extending over the apertures 31 and engaged by the bolts 33 already mentioned. It carries a latch or locking bolt 36 adapted to engage in a slot 37 in the bar 19 and when 25 so engaged prevents upward movement of the bar to release the tongues 27 from the notches 28 of the straps 25. A barrel 38 extends through the aperture 29 and may be turned from the outside either by a key or 30 by the combination handle to withdraw the locking bolt and permit the opening of the locker.

Considering now the locking device adapted to be secured by a padlock, it will 35 be noted that in the present instance this device comprises a plate 41 and a latch or locking member 42. The plate 41 is provided with two wings 43 having apertures 44 through which the bolts 33 may be and 40 are secured when the construction is arranged as shown in Figs. 1 to 5. The plate 41 has an inclined slot 45 extending upwardly and toward the side of the door provided with the plate 19. The latch 42 is positioned 45 through this slot and this latch comprises a strap of transverse section approximating that of the slot. The strap is bent centrally at 46 to provide a locking or latch arm 47 on the inside of the locker and a padlock 50 engaging and manipulating arm 48 on the outside. The arm 48 is movable through the slot 45 and is twisted at 49 so that a cam action results from the movement of the latch causing the arm 42 to have a pivotal 55 movement as may be seen by comparing Figs. 2 and 3, Fig. 2 showing the position of the latching arm 47 when the arm 48 is pulled completely through the slot 45 and Fig. 3 showing the position of this latch 60 when the operating arm is pushed completely in. Two studs 51 and 52 are provided upon the arm 48 to limit the inward and outward movement of the member 42. The latch when in outer position, i. e. the 65 position shown in Fig. 2, engages the bottom

of the slot 37 and prevents lifting of the latch bar 19 to release the door, and when in position shown in Fig. 3 it is lifted above the bottom of this slot and the handle 21 may be manipulated to lift the latch bar 70 and open the door.

The arm 48 is provided with an opening 53 in which may be engaged a padlock 54 and this aperture is so arranged that the padlock can only be engaged when the arm 75 48 has been pulled to the outer limit of its movement through the slot 45; i. e. when the latch 47 is in locked position.

The two locking devices may be interchanged one for the other and a standard 80 door may be made up to receive either as the individual orders may require.

It is thought that the invention and many of its attendant advantages will be understood from the foregoing description, and it 85 will be apparent that various changes may be made in the form, construction and arrangement of the parts without departing from the spirit and scope of the invention or sacrificing all of its material advantages, 90 the form hereinbefore described being merely a preferred embodiment thereof.

I claim:

1. In a locker, the combination of a door 95 having a rim lock receiving aperture, and a pad lock receiving device adapted to be positioned in the rim lock receiving aperture, and having a part protruding from the door and a locking part disposed behind the door.

2. In a locker, the combination of a door having a rim lock receiving aperture, and a padlock receiving device adapted to be positioned through said aperture, said device comprising a plate having an elongated 105 slot behind said aperture, and a bent strap movable through said slot and arriving at locked position when a portion through said slot is pulled to its outermost limit, said strap having an aperture in its outer portion for receiving a padlock.

3. A padlocking device for a locker door, comprising a cam latch adapted to protrude through the door and to receive a padlock when in locking position, and a padlock for 115 engaging said latch when in locked position, the padlock passing only through said latch when said latch is in locked position.

4. In a locker, the combination of a door member, a jam member adjacent the free 120 edge of said door member when the door is closed, and a movable padlocking engaging device disposed through one of said members and adapted to engage the other, said padlocking engaging device being movable lengthwise into and out of operative position.

5. In a locker, the combination of a door having a rim lock receiving opening, and a padlock receiving device adapted to be dis- 130

posed through said opening, and means for securing said padlock receiving device in position.

6. In a locker, the combination of a door 5 having a rim lock receiving aperture, and holding plate, and a pad lock receiving device disposed through the aperture and engaged by said holding plate.

7. In a locker, the combination of a door 10 having a lock receiving aperture and a pad

lock receiving device adapted to be positioned through said aperture, said device comprising a cam latch and a slotted plate adapted to be held to the door.

Signed in the presence of two subscr- 15
ing witnesses.

WALTER N. VANCE.
